United States Patent Office

Des. 206,357
Patented Nov. 29, 1966

206,357

COMPOSITE LIQUID CONTAINER OR SIMILAR ARTICLE

John Donald Sullivan, 59 Elva Ave., Killara,
New South Wales, Australia

Filed Oct. 15, 1965, Ser. No. 87,490

Term of patent 14 years

(Cl. D58—17)

Fig. 1.

Fig. 2.

Fig. 3.

Fig. 4.

FIG. 1 is a perspective view of a composite liquid container or similar article showing my new design wherein the smaller liquid container is fitted into the opening provided in the larger liquid container;

FIG. 2 is an end elevational view showing the end opposite that seen in FIG. 1;

FIG. 3 is a side elevational view showing the side opposite that seen in FIG. 1; and

FIG. 4 is a top plan view thereof.

I claim:

The ornamental design for a composite liquid container or similar article, substantially as shown.
